**COMBINED PEG HEAD, NECK AND FINGER
BOARD OF A GUITAR OR SIMILAR ARTICLE**

Charles A. Gauvin, 805 S. Water St.,
Silverton, Oreg. 97381

Filed Dec. 7, 1967, Ser. No. 9,680

Term of patent 14 years

Int. Cl. D17—03

U.S. Cl. D56—1

FIG. 1

FIG. 2

FIG. 3

FIG. 1 is a front elevational view of a combined peg head, neck and finger board of a guitar or similar article, showing my new design;

FIG. 2 is a left side elevational view; and

FIG. 3 is a cross-sectional view taken on line 3—3 in FIG. 1.

I claim:

The ornamental design for a combined peg head, neck and finger board of a guitar or similar article, substantially as shown.
